[57] CLAIM

The ornamental design for a counter top for a sink and accessory containers, as shown and described.

DESCRIPTION

FIG. 1 is a perspective view from the top, front and right side of a counter top for a sink and accessory containers showing our new design;

FIG. 2 is a top plan view thereof;

FIG. 3 is a front elevational view thereof, the rear elevational view being the mirror image of the front;

FIG. 4 is a left side elevational view thereof;

FIG. 5 is a right side elevational view thereof;

FIG. 6 is an enlarged cross-sectional view taken on line 6—6 of FIG. 2;

FIG. 7 is an enlarged cross-sectional view taken on line 7—7 of FIG. 2;

FIG. 8 is an enlarged cross-sectional view taken on line 8—8 of FIG. 2;

FIG. 9 is an enlarged cross-sectional view taken on line 9—9 of FIG. 2;

FIG. 10 is an enlarged cross-sectional view taken on line 10—10 of FIG. 2; and,

FIG. 11 is an enlarged top plan view of a second embodiment thereof.

The broken line representation of a hole in FIG. 1 is for the purpose of illustration only and forms no part of the claimed design.
